UNITED STATES PATENT OFFICE.

JOHN F. FITCH, OF BUCHANAN, VIRGINIA.

VENDING MACHINE.

Application filed November 16, 1920. Serial No. 424,476.

To all whom it may concern:

Be it known that I, JOHN F. FITCH, a citizen of the United States, residing at Buchanan, in the county of Botetourt and State of Virginia, have invented certain new and useful Improvements in Vending Machines, of which the following is a specification.

This invention relates to improvements in vending machines and has for its object to provide a novel and interesting coin-controlled vending machine.

Another object of the invention is to provide a vending machine having an element of chance.

A further object of the invention is to provide in a coin-controlled vending machine means whereby the operator may receive an ordinary package, two of said packages, or a prize package, the vending of said packages being controlled by chance.

A still further object of the invention is to provide in a coin-controlled vending machine means whereby a coin may be dropped into any one of a number of slots whereby the machine may be operated.

A still further object of the invention is to provide in a coin-controlled vending machine means whereby a coin actuates the vending device.

With the above and other objects in view, which will hereinafter more fully appear, I have invented the device illustrated in the accompanying drawings in which:

Fig. 1 is a front elevational view of my vending machine,

Fig. 2 is a top plan view thereof,

Fig. 3 is a section taken on line 3—3, Fig. 2,

Fig. 4 is a section taken on line 4—4, Fig. 1,

Fig. 5 is a similar view showing an operated position of certain of the mechanism,

Fig. 6 is a longitudinal sectional view of the device,

Fig. 7 is a detailed elevational view of the package cabinet.

Like reference characters indicate like parts throughout the following specification and in the several views in the drawings in which 1 is a coin-controlled vending machine adapted for the purpose of vending packages of chewing gum, candy, prize packages, cigars, or other articles, and con-

sists of a cabinet 2 having a package chute 3 in the bottom thereof, and a money drawer 4 located just above said chute. The cabinet extends upwardly at the bottom as at 5 to provide space for said chute and money drawer. The front of the cabinet is enclosed by a glass window 6, which exposes a coin guiding board 7 in which is secured a plurality of pins 9, which are outlined by other series of pins 10. The first series of pins are arranged in a number of horizontally disposed rows, the pins of each row being offset from the pins of the adjoining row so as to provide a series of vertically disposed rows of pins, each row being offset from the other row. The pins 9 are so spaced that a coin may pass between any two thereof, and as a coin descends, after being dropped in the slot 11 which directs the same between the series of pins 10 from whence it is caused to drop in between the pins 9, it may take any course in its descent toward the coin slots 12, 13, 14, 15, and 16. Four curved lines of pins 17, 18, 19, and 20, together with the row of pins 10, are adapted to direct the coin into one of the slots 12, 13, 15, or 16, and the rows of pins 18 and 19 are adapted to direct the coin to the slot 14 provided the same falls between said latter rows of pins. Directly below the board 7 is a shelf 21 upon which a package cabinet 22 is removably seated, guides 23, 24, 25, and 26 directing said cabinet to its position on said shelf 21, said package cabinet being provided with a series of channels 27, 28, 29, 30, and 31, for packages 32, 33, 34, 35, and 36, each of said stacks of packages being held in their respective channels by division walls 37 which are T-shaped in cross section, said walls having lower right-angular indented extensions 40 which project a certain distance below the lower edge 38 of the back board 39 of said cabinet, said several stacks of packages seating normally upon said indented extensions 40. The distance between said lower edge 38 and said extensions 40 is arranged according to the thickness of any one or more packages it is desired to vend from any channel. Each of said channels 27 to 31 respectively align with slots 41, 42, 43, 44, and 45 in said shelf 21. In each of said slots are slidably mounted blocks 46, 47, 48, 49, and 50, each having side grooves 51

and 52 operating upon the edges 53 and 54 formed by said slots. Each of said blocks 46 to 50 respectively, are of a height determined by the space between the edge 5. 38 of the member 39 and the right-angular extensions 40, so that said blocks when passing under said channels 27 to 31 respectively will carry out one or more of the packages in said stacks 32 to 35 respectively. Horizontally movable under the shelf 21 is an operating device for said blocks 46 to 50 inclusively, said device consisting of a rack 55 which is provided with channel members 56, 57, 58, 59 and 60 which 10 operate directly under said slots 41 to 45 respectively, and into which centrally disposed independent tongues 61 of each of said blocks 46 to 50 project. Each of said channels are provided with indented flanges 62 and 63 which normally operate free of said tongues 61. However, when the coin drops into any one of the coin slots 12 to 16, the same falls upon the fixed strip 64 mounted under said rack 55, and between 15 said tongues 61 and said flanges 62 and 63 of any of said channel members, in order that when said member 55 is moved rearwardly the coin will be caused to force the particular block upon which it seats rearwardly, said block in turn causing one or 20 more packages, as desired, to slide from off said member 40 and fall into the chute 3 from whence it may be reached by the operator. Mounted on the rear part 65 of 25 the member 55 are a pair of rods 66 and 67, the upper ends of which are fixed to a crank rod 68 mounted in the side walls 69 and 70 of the cabinet 1, said rod projecting through the wall 70 and being turned 30 at right angles to form an operating lever 40 71 therefor, said lever projecting through a slot 72 in the bracket 73 on said side wall 70 whereby its movement is controlled. To the center of the rod 68 is fixed a lever 45 74, to the free end of which is fixed a spring 75, the other end of which is connected to the bottom of the cabinet 1, said spring holding said lever normally down, which in turn holds the rack 55 in a forward position. The rack, 55, is proportioned to engage the rear sides of all of 50 the blocks, 46 to 50, and when returned by the spring, 75, forces to normal position any one of said blocks which has been moved to ejecting position as noted.

When a coin is dropped into the coin slot 11 and is directed through the pins 9 to the slot 12, a prize or other package in channel 27 is vended on the movement 60 of the lever 71. When the coin is directed to slot 13, as shown in the present construction, two packages of gum are vended by the machine. When the coin is directed to slot 14 one package is vended, etc.

65 Located directly under the strip 64 is

a money drawer 4 into which the coin drops after the rack 55 carries the same beyond said strip.

A hinged top 76 is provided over the package cabinet 22, the same being provided 70 with a lock 77.

Having now described my invention that which I claim is new and desire to procure by Letters Patent is:

1. A check controlled vending machine 75 comprising a plurality of commodity stacks, ejectors for the stacks, each proportioned and contoured to eject a predetermined number of its corresponding commodity packages, means supporting the ejectors to slide freely to ejecting position, a spring-tensioned grid mounted to slide, said grid embodying a plurality of slots each embracing one of the ejectors and having a common side positioned to force all of said ejectors to normal positions simultaneously, the proportions and relations of the said slots and ejectors being such that the grid may slide freely against the tension of the spring without affecting the ejectors, means to employ a check in any slot as a connector between that slot and the embraced ejector, chance controlled means to determine the introduction of the check into one of the several connecting positions, manual means to move the grid against the tension of the spring to actuate an ejector connected by the check and a receptacle positioned to receive the check when released by the release of manual stress.

2. A check controlled vending machine comprising a plurality of commodity stacks, ejectors for the stacks each proportioned and contoured to eject a predetermined number of its corresponding commodity packages, 105 ribs supporting the ejectors to slide freely to ejecting positions, a spring-tensioned grid mounted to slide, said grid embodying a plurality of slots each embracing one of the ejectors and having a common side positioned to force all of said ejectors to normal positions simultaneously, the proportions and relations of said slots and ejectors being such that the grid may slide freely against the tension of the spring without affecting the ejectors, means to employ a check in any slot as a connector between that slot and the embraced ejector, chance controlled means to determine the introduction of a check into 110 one of the several connecting positions, manual means to move the grid against the tension of the spring to actuate an ejector connected by the check and a receptacle positioned to receive the check when released by the release of manual stress.

3. A check controlled vending machine comprising a plurality of commodity stacks, ejectors for the stacks each proportioned and contoured to eject a predetermined number 115 of its corresponding commodity packages,

- means supporting the ejectors to slide freely to ejecting position, a grid mounted to slide, a spring controlled lever engaging said grid and tending to move said grid to the limit 5 of its movement, said grid embodying a plurality of slots each embracing one of the ejectors and having a common side positioned to force all of said ejectors to normal positions simultaneously, the positions and 10 relations of said slots and ejectors being such that the grid may slide freely against the tension of the spring without affecting the ejectors, means to employ a check in any slot as a connector between the slot and the 15 embraced ejector, chance controlled means to determine the introduction of a check into one of the several connecting positions, manual means to move the grid against the tension of the spring to actuate an ejector 20 connected by the check and a receptacle positioned to receive the check when released by the release of manual stress.
4. A check controlled vending machine comprising a plurality of commodity stacks, 25 ejectors for the stacks each proportioned and contoured to eject a predetermined number of its corresponding commodity packages, means supporting the ejectors to slide freely to ejecting positions, a spring-tensioned grid mounted to slide, said grid embodying a plurality of slots each embracing one of the ejectors and having a common side positioned to force all of said 30 ejectors to normal positions simultaneously, the proportions and relations of said slots and ejectors being such that the grid may slide freely against the tension of the spring without affecting the ejectors, a cover for said slots provided with a plurality of perforations each disposed over one of the said slots, a chance device for directing a check into some one of said perforations and into some one of the connecting positions, manual means to move the 35 grid against the tension of the spring to actuate an ejector connected by the check, and a receptacle positioned to receive the check when released by the release of manual stress.
- 40 In testimony whereof I affix my signature in the presence of two witnesses.
